[57] CLAIM

The ornamental design for a portion of a make-up planner, as shown and described.

DESCRIPTION

FIG. 1 is a perspective view of a portion of a make-up planner with an insert showing my new design;

FIG. 2 is a right side elevational view of the insert for the portion of a make-up planner of FIG. 1;

FIG. 3 is a bottom plan view of the insert of FIG. 2;

FIG. 4 is a front elevational view of the insert of FIG. 2;

FIG. 5 is a rear elevational view of the insert of FIG. 2;

FIG. 6 is a perspective view of an alternate embodiment of the portion of a make-up planner with an insert showing my new design;

FIG. 7 is a right side elevational view of the insert for the portion of a make-up planner of FIG. 6;

FIG. 8 is a bottom plan view of the insert of FIG. 6;

FIG. 9 is a front elevational view of the insert of FIG. 6; and,

FIG. 10 is a rear elevational view of the insert of FIG. 6.

The broken line showing of a binder in FIGS. 1 and 6 is for illustrative purposes only and forms no part of the claimed design.
